UNITED STATES PATENT OFFICE

SOUND-DEADENING AND BALANCING
MEANS FOR RAILWAY WHEELS

Michael Watter, Philadelphia, Pa., assignor to
The Budd Company, Philadelphia, Pa., a cor-
poration of Pennsylvania

Application August 19, 1949, Serial No. 111,149

2 Claims. (Cl. 295-7)

1

The invention relates to railway car wheels, and particularly to sound-deadening means for such wheels which can also be readily used as balancing means for the wheels.

The railway-travelling public is becoming more and more noise conscious and a sizable proportion of the noise resulting from railway car operation has been traced to the wheels. Various means have been proposed to silence the noises arising from the high frequency vibrations of the wheels, but so far none of these has furnished a satisfactory solution of the problem.

It is a main object of the invention to provide a sound-deadening attachment for the wheels of a railway car, which is simple in form, readily attached to the wheel and which effectively deadens the sounds emanating from the wheels.

It is a further object of the invention to combine with such sound-deadening means a means whereby the wheels may be readily balanced. Heretofore, such unbalance has resulted, particularly in high speed operation, in further increase in noise and increased wear on the wheels and rails and on the parts associated therewith.

These objects are in a large part attained by securing, to a readily prepared undercut annular seat or seats on the radially inner side of the rim of a wheel, a continuous sound-deadening ring or rings of a material, preferably mainly metal, differing from the material of the wheel, and by associating with such ring or rings means for readily bringing the wheel into balance, as by forming an integral enlargement on the radially inner side of the ring at one portion of its circumference.

These and other objects and the manner in which they are attained will become evident from the following detailed description when read in connection with the drawings forming a part of this specification.

In the drawings:

Fig. 1 is an elevational view of a wheel equipped with the invention as seen from the outside;

Fig. 2 is a sectional view of the wheel, the section being taken substantially along the line 2-2 of Fig. 1;

Fig. 3 is a sectional view of the sound-deadening ring prior to its assembly with the wheel; and

Fig. 4 is an enlarged fragmentary view of a portion of the ring, showing it in greater detail.

The railway car wheel shown in the drawings is a usual forged and machined car wheel, of iron or steel, having a hub portion 10, a wheel body web 11 and a rim 12 projecting axially on

2

opposite sides of the web. In machining the rim, the undercut seat or seats 13 may be readily formed on the radially inner faces of the rim. In the drawings, two such seats 13 are shown formed at the opposite sides of the rim and the sound deadening means, while shown applied to but one of these faces may, if desired, be applied to both.

Tests have shown that very good results are attained with but one sound-deadening ring, and it is believed that ordinarily one ring will suffice.

The sound-deadening ring is generally designated by 14. It is preferably made of two rings 15 and 16 of a metal, such as brass, different from that of the wheel, joined by a thin annulus of rubber 17 vulcanized to the rings. The radially outer face of the ring 14 is inclined similarly to the inclination of the undercut seat 13 on the radially inner face of the rim, and the axially inner ring 16 may be bevelled as at 18, to clear the enlargement 19 of the web 11 where it joins the rim 12 of the wheel.

The ring 14, prior to its insertion in the wheel, is made of somewhat larger diameter than the diameter of the seat 13. It is then cooled to a low temperature, as by packing it in Dry Ice, which causes it to shrink to a diameter permitting it to be moved axially in alignment with the seat 13 on the wheel rim. As it returns to normal temperature it expands and becomes securely locked to the seat 13 so as not to loosen under normal operating conditions.

By actual test it has been found that the dimensions of the ring are more or less critical, the best results having been obtained by a ring of approximately $\frac{1}{4}$ sq. in. cross-section used with the ordinary size car wheels.

Such a ring can be readily used also to balance the wheels, which are normally found to be out of balance, sometimes as much as several pounds. To this end the ring 14 is formed on its radially inner side and at one portion of its circumference by an integral inward enlargement or projection 20. To balance the wheel, the ring is inserted in the wheel, with this projection opposite the heavy side of the wheel, and the weight is then adjusted to the proper amount to correct the unbalance by grinding or machining off a portion of the projection, as indicated by the dotted line 21 in Fig. 1.

While a specific form of the invention has been described herein in detail, it will be understood that changes and modifications may be made by those skilled in the art without departing from the spirit and scope of the invention.

What is claimed is:

1. In a railway wheel, a rim having an annular face on its radially inner side and a continuous sound-deadening ring of a material differing from that of the wheel secured tightly on said face, said ring comprising two metal annuli seated on said face and interconnected with each other by a rubber annulus.

2. In a railway wheel, a rim having an annular face on its radially inner side and a continuous sound-deadening ring of a material differing from that of the wheel secured tightly on said face, said ring comprising two metal annuli seated on said face and interconnected with each other by a rubber annulus, at least one of said metal annuli having an integral radially enlarged portion thereon for balancing the wheel.
